WILLIAM C. GOULD, OF LOS ANGELES, CALIFORNIA

SPED CONTROL FOR ELECTRICAL TYPEWRITERS

Application filed May 14, 1930. Serial No. 452,305.

The object of my invention is to provide a means for causing the capital letters of an electrically actuated typewriter to strike the platen with greater force than the lower case letters, thus compensating the greater contact area of the capitals and producing a balanced or even impression of the upper and lower case letters.

My invention is applicable to the class of typewriter in which the type-bar is actuated by a friction cam which is brought into contact, by a slight movement of the finger key, with a roller revolving at a constant speed. In some machines of this class the roller is smooth, the engaging surface of the cam is roughened and, on contact with the roller, the cam describes a semirevolution before coming to rest. In others the surface of the roller is roughened and the cam is replaced by what is substantially a hook connected to the type-bar mechanism, this hook engaging the surface of the roller and following it until it is kicked off at the limit of its travel.

For the purpose of my invention these two devices are equivalent as each of them actuates the type-bar with a force which, in any given machine, varies directly with the peripheral speed of the roller.

Typewriting machines of the class referred to are well known and understood and are no part of my present invention. In order, however, to make my invention clear it is necessary to state that in these electrically operated machines the roller or its equivalent is driven by a small electric motor the speed of which is controlled by a rheostat. This rheostat is placed in parallel with the motor armature and both are connected in series with a choke coil or other fixed resistance, which may be one of the field windings, by which the power input to the armature is controlled. Connected in this manner the rheostat acts as a shunt for the armature and thus when the rheostat is adjusted to its position of maximum resistance the power input into the motor is at its maximum and vice versa. As the motor is necessarily of the variable speed type the speed of the motor and of the roller which it drives are at their maximum with the rheostat at maximum resistance and at their mini-

mum with the rheostat at minimum resistance, while if the rheostat be cut out completely the motor will receive the full power input which the fixed resistance will pass and will accelerate to a speed greater than that which it will attain with the rheostat in circuit and at maximum resistance.

My invention in its simpler form comprises means for increasing the resistance of the rheostat when the usual shift key is actuated by the operator. This increase in resistance, as above said, increases the speed of the motor and of the roller and causes the upper case letters, which are brought into play by the usual action of the shift key, to be actuated more strongly than the lower case letters. My invention also comprises means by which the degree of increase in resistance may be adjusted by the operator to secure complete evenness of impression between the two cases.

I have further found that a mere increase in the resistance offered by the rheostat must be so limited as to restrain the speed of the motor within a fixed maximum and that when so limited the acceleration of the motor is unduly sluggish. It will be understood that the shift key is used by the operator either to strike a single capital, as the initial letter of a name of a sentence, or to write a word or a line in capitals, and that in the latter case the ultimate speed of the motor must be such as to give the correct weight of impression. Such being the case, it will be obvious that unless the motor accelerates with extreme rapidity a single capital will be struck a lighter blow than will be delivered to succeeding capitals, the weight of the stroke changing so long as the motor speed and the consequent roller speed are undergoing a change.

In order to avoid this difficulty and to obtain the desired rapid acceleration of the motor my invention further comprises means for breaking the rheostat circuit during an extremely brief period of time, thus throwing into the motor a power input much higher than it would tolerate in continued operation and causing it to accelerate with the greatest possible rapidity. This initial

kick having been given to the motor the rheostat circuit is again formed, but at a point where the resistance is increased to a desired degree, and the motor speed is thus brought to and held at a point which will produce 5 the desired weight of impression in case a plurality of capitals are to be struck. This entire cycle of operations takes place automatically, in response to a single depression of the shift key, and with such rapidity that 10 a single capital, such as an initial, formed in the ordinary use of the machine by the most rapid operator, will come up with the same force as the succeeding caps in a line 15 of upper case letters.

15 The spirit of my invention may best be understood by reference to the attached drawings and the following description thereof, in which I show an illustrative embodiment of my invention in connection with 20 certain allied parts of a standard make of electrically operated typewriter. In these drawings, for the sake of clear distinction, I have indicated such parts as belong to the 25 existing machine by means of index letters A, B etc., and the parts of my device by index numbers 1, 2 et seq.

In these drawings Fig. 1 is an isometric projection of certain portions of the frame of 30 the typewriter showing the position of the shift key and the shift rail and of those parts of my device which are located in relation thereto;

Fig. 2 is a rear elevation of the rheostat 35 coils showing the high and low resistance contacts and the low resistance contact breaker in face;

Fig. 3 is a cross section through the rheostat coils and the low resistance contact and breaker;

40 Fig. 4 is an end elevation of the rheostat subframe showing a portion of the low resistance contact breaking mechanism, and

Fig. 5 is a wiring diagram of the machine 45 as modified from its original form by the inclusion of my various devices.

Referring to Fig. 1, A—A, B and C1—C2 are portions of the typewriter frame, which 50 may here be considered merely as fixing the position of certain moving parts. D is the shift cross bar by which the carriage is raised in response to a depression of the shift key, thus bringing the platen into position to receive upper case impressions from the type 55 blocks.

The bar D is raised by an upward movement of the shift lever E which is pivoted at F, this movement in turn being produced by a partial forward rotation of the shift 60 rocker lever G which is rigidly attached to the shift rocker-shaft H. This shaft is journaled at I—I and is rocked by means of mechanism which need not be further traced, it being sufficient to say that this mechanism 65 is responsive to a depression of the shift key

and that in so responding the lever G swings forward or in a right hand direction.

J is the shift key lever which is pivoted at K on a fixed part of the machine not shown. L—L are the two shift keys and M the shift lock key. N is the shift rocker rod by means of which a movement of the right hand key is transmitted to the left hand bar. This rod is bent at each end into the form of a crank which is pivoted at O—O as shown, and when the shift key is depressed these cranks swing 75 downwardly.

It will be understood that the above are parts of the existing typewriting machine to which, for illustrative purpose, I apply certain parts of my device, and that they are 80 not of my invention.

Referring again to Fig. 1, 1 is a rocker lever which is firmly attached to the end of the shift rocker rod N near the pivot point O. When the shift key is depressed the lower end of this lever moves backward or in a left hand direction, carrying with it the push rod 2 which is pivoted into the lower end of lever 1 as at 3.

The box 4—4 may be of metal, fiber or other suitable material and is fastened inside the typewriter frame in any suitable manner as by means of screws passed through the lugs 5—5. A block 6, preferably of fiber or other insulating material, is attached at 7 to the end of the push rod and is thus caused to reciprocate within the box as the push rod is actuated by lever 1 in response to movement of the shift key L. This block may be maintained in an upright position by means of a bearing rod 8 and a compression spring 9 may be used to take up lost motion and return the block to its forward or retracted position. Through the upper part of the block 1 I pass a metallic conducting stud 10 to which 105 I attach the terminal 11 of a conducting cable 12.

To one lug of the box I fasten a bent strap 13 which is preferably of metal but which 110 must be insulated from the frame of the machine and therefore from the box if the latter is metallic. From each end of this strap I project inwardly the contact points 14a—14b, preferably adjustable as to length and so adjusted that when the block 6 is in the forward position the front end of the stud 10b forms an electrical contact with the point 14b, while on depression of block 6 to its rearward limit the stud 10a contacts with point 14a. These two points 14a—14b must be in 115 electrical communication with each other and with the terminal 15 of the cable 16.

By means of this device the circuit through 125 the rheostat, which is a part of the typewriting machine, is broken and remade as will be disclosed.

Referring now to Figs. 2 and 3, P—P are 130 separated coils of resistance wire wound on

insulating and heat resisting cores and mounted back of the frame element C2 (see Fig. 1) in a position paralleled to the rod D. These coils are provided with conducting cables 12 and 17 but the sole connection between them is through the bridges 18 and 19, which are movable in a right and left direction and which, with the coils, form a rheostat for controlling a certain circuit within the motor 10 and thereby varying the speed of the motor, as will be disclosed. On moving bridge 18 to the right or away from the terminals, or by breaking the circuit through bridge 18 and leaving bridge 19 in contact, the length 15 of resistance wire through which the current flows is increased, and with it the resistance interposed between the terminals 12 and 17.

Bridge 18 is based on a block 20 of fiber or other insulating material which is threaded 20 to engage the long screw 21. This screw is restrained against end movement and is rotated by means of a thumb wheel 22, the bridge being thereby moved to right or left as preferred.

25 The bridge proper consists, first, of two contact arms 23 and 24, each of which bears on one coil and is made fast to the block. These arms are insulated from each other and are connected only by closing the make 30 and break about to be described.

An outer arm 25 of spring metal is in one piece and is permanently in contact at its upper end with the upper arm 23. At the lower end of arm 24 and in a corresponding 35 position on the spring arm 25 are placed contact points 26, and the lower end of the spring arm is connected to an extension spring 27 which is adapted to be moved backward by a movable rod 28. On moving the 40 rod in this direction the contact points are separated, while a contrary movement permits the spring 25 to bring them together and to complete a connection between the two coils P.

45 The means by which the contact points 26 are separated and the circuit normally existing through the coils P and the bridge 18 broken are indicated in parts in Figs. 1 to 4 inclusive. In Fig. 1 a stiff wire 29 is shown as passed through the upper end of lever G and as this lever swings forward to raise the carriage in response to a depression of the shift key the wire 29 is also pulled forward.

In Fig. 4, which is an end elevation of the 55 resistance coil housing, the opposite end of this wire is shown as passing through the upper end of a crank 30 which is affixed to an end of the rod 28. This rod is journaled in the coil housing as at 31-31 and is bent 60 downwardly as at 32-32 to form a double crank. This crank moves backward in response to a pull on the wire 29 and thus flexes the spring 27 and separates the contact points 65 26. It is desirable to provide a screw nut 33 on the end of wire 29 to adjust the throw of

crank 28 and the time of separation of the contacts 26.

Bridge 19 is based on a block 34 which should be of insulating material and of the same form as block 20. Block 34, however, need not necessarily be threaded to engage 70 long screw 21 but may merely have a hole through which the screw passes freely. The spring 35 is formed of one piece of metal and bears permanently on both coils, thus establishing a permanent electrical connection between them at a point farther from the terminals 12-17 than that at which bridge 18 connects them. Therefore the resistance 75 through the circuit 12-19-17 which comes into operation when bridge 18 is rendered inoperative by separating the contact points 26 is greater than that of the circuit 12-18-17 which is established when the 80 points 26 are in contact.

85 The block 34 may be retained in any desired position merely by the tension of the spring 35 and the friction of its tips on the coils, being thus movable by hand if it is desired to increase or decrease the resistance of the 90 circuit 12-19-17. This simple method seems to be quite sufficient in practice, but if preferred the block may be passed through a slot formed in the cover plate and retained in a movably fixed position by clamps, or it may 95 be threaded into the long screw so as to move in unison with block 20 and at a fixed distance therefrom when the screw 21 is revolved by the thumb wheel 22.

The electrical connections through which 100 my device operates may be understood with reference to Fig. 5, which is strictly diagrammatic. The motor which constitutes the prime mover in the illustrative typewriting machine is a high speed universal motor 105 adapted to either direct or alternating current. This motor has the armature Q, the commutator R, the two brushes S1-S2 and the two field coils T1-T2. The field T1 is connected in series with the armature and 110 to the main power leads, while the field T2 is on a shunt which includes the armature windings and the rheostat. It is in this shunt that I place the make and break indicated at 4 in Fig. 1 and the rheostat bridges indicated 115 at 18 and 19 in Fig. 2.

Tracing out the main circuit, the power lead 36 passes through a switch 37 to the brush S2, through the armature windings to the brush S1, through the lead 38 to the field 120 T1 and thence to the power lead 39. The leads 36 and 39 are fused in the customary manner as at 40 and 41.

Tracing out the shunt circuit, the main lead 36 is connected by the lead 42 to the field 125 coil T2 and by the lead 16 to the box 4 which, as already described, has the contact points 14a and 14b. Either one of these points establishes a connection through the studs 10 and the lead 12 to the lower rheostat coil, 130

thence through the bridge 18 (or through the bridge 19 if the contacts in bridge 18 be separated, to the upper rheostat coil, thence through the lead 17 to the brush S1 and 5 through the armature windings back to the lead 42 and the field coil T2.

The device illustrated functions in the following manner. When the shift key L is depressed the arm 1 swings rearwardly and 10 imparts a corresponding movement to the rod 2 and the block 6, thus separating the contact points 10b and 14b and breaking the shunt circuit. When the shift key is completely depressed the block 6 has moved back to the 15 limit of its travel and the contacting points 10a and 14a are brought together, thus remaking the shunt circuit through the rheostat. An extremely brief but material interval of time elapses between the separation of 20 the contacts 10b and 14b and renewal of the contact between 10a and 14a and during this time interval the shunt circuit is broken and the full power load is thrown on the single field coil T1 and the armature windings, thus 25 giving the motor its maximum power input and causing it to accelerate with extreme rapidity.

Synchronously with the movement of the block 6 and during the brief time interval mentioned certain mechanism, which is a part of the typewriting machine, causes the lever G to rotate to lift the carriage and bring the platen into position to receive a capital letter impression. This movement of the lever G 35 imparts a similar movement to the wire 29 and the crank 30 and a reverse or backward movement to the bent rod 28. This backward movement of the rod 28 acts to separate the contact points 26 and to break the circuit 40 12-18-17, while the circuit 12-19-17 (which has a greater resistance) remains closed. It will thus be seen that, as there is a certain amount of lag to the movement of the arm G, due to the time required for the 45 cam which actuates this arm to come into function, a depression of the shift key produces three successive functions: first, the breaking of the shunt circuit and the rapid acceleration of the motor; second, the opening of the contacts 26 and of the lower 50 resistance circuit through the rheostat, and third, the remaking of the shunt circuit through the rheostat coils and the fixed bridge 55 through a resistance greater than that previously existing, thus permitting the motor to operate continuously, if desired, at a speed greater than that prevailing prior to the depression of the shift key but less than the speed at which it would operate with the 60 shunt circuit interrupted.

On the release of the shift key these functions are reversed in order and the motor is decelerated, by the remaking of the lower resistance circuit through the rheostat, to the 65 speed at which it should operate to give the

proper impression to the lower case letters.

While I have described my device as applied to a motor having a rheostat in a shunt around the armature and which therefore increases in speed when the shunt circuit is broken, I do not limit myself to this specific application. It will be obvious that a reversal of the functions of the make and break and of the bridge 18 would make my device applicable to a motor in which the rheostat 70 was in series with the armature. In such case the function of the make and break 75 would be to close and then to open a ground or shunt around the rheostat, by which the motor would be suddenly accelerated, while 80 the function of the crank rod 28 would be to close a bridge placed across the rheostat coils at a position of less resistance than that at which the permanent bridge was established, thus governing the speed of the motor at a 85 rate higher than that at which it would revolve with this bridge open.

It should also be understood that the portion of my device which comprises the two bridges 18 and 19 may be usefully applied 90 without the interposition of the make and break 4 in the rheostat circuit. In such case the contacts 26 separate when the platen rises to the capital letter position and the motor accelerates because of the increased 95 resistance thus thrown into the shunt circuit. The acceleration, however, is not so rapid as that which takes place when the shunt circuit is entirely broken by the use of the make and break and with the machine in the hands 100 of a rapid operator the first one or two impressions in a line of capitals would be somewhat lighter than succeeding impressions.

I claim as my invention:

1. In a typewriting machine having a shift key for bringing capital letters into function and a power roller driven by a variable speed electric motor: means responsive to a depression of said shift key for accelerating said motor and said power roller when a capital letter is to be struck. 105

2. In a typewriting machine having a shift key for bringing capital letters into function and a power roller driven by a variable speed electric motor: means responsive to a depression of said shift key for accelerating said motor and said power roller when a capital letter is to be struck and for governing said speed at an increased rate when said shift key is held in a depressed position. 110

3. In a typewriting machine having a shift key for bringing capital letters into function, a power roller driven by a variable speed electric motor and a rheostat adapted to vary the speed of said motor: means responsive to a depression of said shift key for so altering the resistance of said rheostat as to increase the speed of said motor when a capital letter is to be struck. 115

4. In a typewriting machine having a 130

shift key for bringing capital letters into function, a power roller driven by a variable speed electric motor and a rheostat adapted to vary the speed of said motor: means to 5 place the rheostat out of function and thereby to rapidly accelerate said motor; means to so alter the resistance of said rheostat as to govern the speed of said motor at an increased rate, and means to bring said rheostat into function at said altered resistance, all said means being responsive to a single depression of said shift key.

5. In a typewriting machine having a shift key for bringing capital letters into function 15 and a power roller driven by a variable speed electric motor, said motor having a rheostat in shunt with its armature: means responsive to a depression of said shift key for first opening and then closing said shunt circuit 20 and means for increasing the resistance of said rheostat when said shunt circuit is closed.

6. In a typewriting machine having a shift key for bringing capital letters into function, 25 a power roller driven by a variable speed electric motor and two parallel resistance units in shunt with the armature of said motor: a circuit breaker interposed in said shunt circuit and adapted to open said shunt circuit 30 in response to a partial depression of said shift key and to close said shunt circuit in response to a further depression of said shift key; a bridge connecting said units at a point at relatively low resistance; a second 35 bridge connecting said units at a point of higher resistance, and means responsive to depression of said shift key for interrupting the circuit formed through first said bridge.

In witness that I claim the foregoing I 40 have hereunto subscribed my name this 8th day of May, 1930.

WILLIAM C. GOULD.
